PURSE FOR ATTACHMENT TO A BRA

Daniel Wise, Reading, Pa., assignor to Healthwear
Underwear, Inc., Wernersville, Pa.

Filed Nov. 6, 1970, Ser. No. 25,859

Term of patent 14 years

Int. Cl. D2—07

U.S. Cl. D2—400

FIG. 1.

FIG. 3.

FIG. 2.

FIG. 4.

FIG. 5.

FIG. 1 is a perspective view of a purse for attachment to a bra showing my new design;

FIG. 2 is a rear elevational view;

FIG. 3 is a left side elevational view;

FIG. 4 is a front elevational view; and

FIG. 5 is a top plan view.

The dashed lines on the body of the purse indicate a woven material.

I claim:

The ornamental design for a purse for attachment to a bra, as shown and described.
